FEED FOR DRAWBENCHES OR THE LIKE

Leslie Holmes, Belair, and Val F. Harris, Blair Athol, South Australia, Australia, assignors to British Tube Mills (Australia) Proprietary Limited, Kilburn, South Australia, Australia

Application July 2, 1951, Serial No. 234,818

In Australia July 6, 1950

9 Claims. (Cl. 205—7)

1

This invention relates to an improved feed for draw benches or the like and in particular it relates to a feed which will allow the tubes or the like to be readily positioned prior to the commencement of a draw.

In machines where tubes or bars are fed to a forming die it is necessary to position the tubes so that the tag end of same can be projected through the die. In the case of tubes, the tube itself must be positioned over a long rod carrying at its end the inner die which during operation is located within the outer die so that both the inside and the outside of the tube is formed at once.

It will be appreciated, therefore, that it is necessary to position the tube to be formed over this inner die and to then move the assembly into position so that the tag end of the tube, which is a reduced portion arranged to be engaged by the grips of the draw carriage, can be projected through the outer die ready to be gripped.

It is the object of this invention to provide an improved feed which will allow ready positioning of the tubes or the like and movement of same to the drawing or other forming locality.

As the invention has particular adaptation to the feeding of tubes to draw benches an embodiment of this adaptation will now be described with reference to the accompanying drawings in which:

Fig. 1 is a somewhat schematic side elevation of the improved feed mechanism.

Fig. 2 is a plan of same.

Fig. 3 is an enlarged transverse section on line 3—3 of Fig. 1.

Fig. 4 is a section as on line 4—4 of Fig. 3, and Fig. 5 is an enlarged transverse section on line 5—5 of Fig. 1.

The tubes to be fed to the bench are moved from a locality adjacent the bench over die rods 6 which extend rearwardly from the feed position in the usual manner customary with tube drawing machines, the die rods terminating in an anchor block 7 from which is also supported a guide tube 8, the purpose of this tube 8 being to maintain proper alignment of the die rods 6 and also facilitate handling of the tubes to be drawn in their crossover movement.

In the drawings a multi-tube feed has been shown which is suitable for feeding a twin draw bench, that is a draw bench having two dies arranged to operate on two tubes during each draw.

The guide tubes 8, of which there are thus four, are supported at their rear ends by slideable carriages 9 and 10 which operate on slides 11 se-

cured in a main frame 12 which incorporates webbed stiffening channels 13 on which the slides 11 are rigidly held.

At the front end the guide tubes 8 are supported from carriages 15 and 16 which operate on tracks 17 carried from end frames 18, the two carriages being interconnected by a chain 19 in which the carriages form as it were a link, the chain 19 at its one end passing around guide sprockets or rollers 20 and 21 and also around a driven sprocket 22, the chain 19 at the other end passing over guide sprockets 23 and 24 so that as one carriage is moved to the left the other moves to the right and vice versa.

As the slideable carriages 9 and 10 as well as the movable carriages 15 and 16 must cross over during their operation, and as the front ends of the guide tubes 8 of the two sets must be in approximately the same horizontal alignment so that either pair can be projected into the die locality, it is necessary to move at least one of the sets of guide tubes out of alignment during traverse from their loading to their feed position or on their return and for this purpose the carriage 15 has on it a pair of guides 26 in which operate stems 27 which have at their lower ends bearing members 28 in which the guide tubes 8 are slidably held, the stems 27 being adjustably connected at their upper ends to a cross bar 30 which in turn is rigidly coupled to a vertical rod 31 on the lower end of which is a roller 32 and near the top of which is a collar 33 which operates with the top plate 34 of the carriage to limit the downward movement of the stems 27 and thus the guide tubes 8.

The other movable carriage 16 is also provided with bearing blocks 36 in which the other pair of guide tubes 8 are slideable, these bearing blocks being also adjustable in height by means of adjusting screws 37 engaging the bottom frame member 38 of the carriage.

Supported by this movable carriage 16 is a double ramp 40 so arranged that during the crossover this ramp will be engaged by the roller 32 and will thus move the stems 27 upwardly in their bearings 26, thereby carrying the tubes 8 upwards so that there is no fouling of the two sets of tubes 8 during the crossover. The movable carriages 15 and 16 are provided with wheels 41.

As it is necessary to line up the other ends of the guide tubes 8, the slideable carriages are in this case spaced apart so that the crossover can be effected without fouling, the two sets of tubes 8 being disposed at a very slight angle to each other as shown more particularly in Fig. 1 so

that while at the rear end they do not change their horizontal alignment they are at the front end in approximately the same horizontal plane.

To effect the changeover of the slideable carriages 9 and 10 a pair of chains 45 and 46 is used, each of the chains 45 and 46 including the carriages 9 and 10 in their continuity so that the spaced relationship of the carriages will, under all circumstances, be maintained.

The chains 45 and 46 pass around driver 10 sprockets 47 at the one end and idler sprockets 48 at the other end, these sprockets being suitably supported in the frame members 11 and 12.

As it is necessary to move the guide tubes 8 together with the die rods 6 in same axially during the crossover from the loading to the position where they feed the draw bench, rear guide members 50 support in same pneumatic cylinders 51 the piston rods 52 of which are connected to the anchor blocks 7 so that reciprocation of the piston rods 52 will cause the anchor blocks to slide forward and backward, the pneumatic cylinders 51 being fed from any suitable supply.

The frames 53 are rigidly secured to the slideable carriages 9 and 10.

As it is also necessary to exactly fix the longitudinal position of the die rod 6 so that the dies on the end of same can be brought into correct alignment with the outer dies with which they cooperate a vernier adjustment is provided for the assembly which consists of a motor 56 for each of the guide tubes 8, this motor being secured upon the appropriate frame member 53 and being connected by means of a chain 57 to a sprocket upon a shaft 58 which has on it a worm wheel 59 in engagement with a toothed nut 60 operating on a threaded portion of the cylinder 51 so that by operating the motor in either a forward or reverse direction a vernier adjustment of the position of the cylinder 51 is given which will also determine the exact forward position of the die rods 6 because of the interconnection.

As damage to the mechanism would result if a crossover could be effected while the guide tubes 8 are forwardly projected, a switch 62 is associated with each of the guide tubes 8, the switch being fixed to the appropriate frame member 53 and being actuated by means of a spring-loaded plunger 63 slideable in a block 64 secured to the anchor block 7 of that guide tube 8, the purpose of this arrangement being to break the circuit to the main driving motor which effects the changeover when the guide tubes 8 are not all fully retracted.

The actual drive for the changeover is derived from a motor 70 which is coupled to a pair of shafts 71 and 72 through hydraulic means comprising a pump 73 and a pair of hydraulic cylinders 74 and 75, the pistons of which are connected to the two ends respectively of a chain 76 which passes around a sprocket 77 coupled to the shafts 71 and 72. A valve controls the flow of hydraulic fluid alternately to the cylinders 74 and 75, the opposite cylinder exhausting as one is supplied.

An angle gear 80 connects the shaft 71 to the shaft 81 and a further angle gear 82 connects this shaft to the shaft 83 on which the sprocket 47 is mounted.

The drive to the sprocket 22 of the other unit is taken from the shaft 72 through the angle gear 85 to the shaft 86, through another angle gear 87 and thence to the shaft 88 on which the sprocket 22 is fixed.

To provide the required rigidity for the two 75

pairs of guide tubes 8, bracing members 90 project downwardly from the one set of tubes while bracing members 91 project upwardly from the other set.

The guide tubes 8 are made telescopic at their front ends, the portion 95 being slideable with respect to the main portion of the tubes 8 but being normally forwardly extended by springs 96 encircling the tubes.

What we claim is:

1. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, means to cause both rear and front carriages to cross over synchronously, means supporting the rear portions of the guide tubes from the carriages in the rear frame, means supporting the forward portions of the guide tubes from the carriages of the forward frame, and means on at least one said carriage in the forward frame to cause the guide tube supporting means to move out of the path of the other guide tube supporting means during a cross-over.

2. Improved feed mechanism for draw benches according to claim 1 characterised by slides in the rear frame and slide engaging members on the said carriages in the rear frame arranged to take the pull of the die rods without dislodging the carriages.

3. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, means to cause both rear and front carriages to cross over synchronously, means slidably supporting the rear portions of the guide tubes from the carriages in the rear frame, means slidably supporting the forward portions of the guide tubes from the carriage of the forward frame, means on at least one said carriage in the forward frame to cause the guide tube supporting means to move out of the path of the other guide tube supporting means during the cross-over, and means to move the guide tubes and die rods axially to allow retraction of same during the cross-over movement.

4. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, means to cause both rear and front carriages to cross over synchronously, anchor blocks slidably supporting the rear portions of the guide tubes from the carriages in the rear frame, means slidably supporting the forward portions of the guide tubes from the carriage of the forward frame, means on at least one said carriage in the forward frame to cause the guide tube supporting means to move out of the path of the other guide tube supporting means during the cross-over, fluid operated means disposed between the rear carriages and the anchor blocks to allow the anchor blocks to be axially moved to retract the guide tubes and die rods during the cross-over, and switch means on the carriages to prevent cross-over excepting when the guide tubes and die rods are retracted.

5

5. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, means to cause both rear and front carriages to cross over synchronously, means slidably supporting the rear portions of the guide tubes from the carriages in the rear frame, means slidably supporting the forward portions of the guide tubes from the carriages of the forward frame, means on at least one said carriage in the forward frame to cause the guide tube supporting means to move out of the path of the other guide tube supporting means during a cross-over, fluid operated means carried by the carriages of the rear frame and coupled to retract the guide tubes and die rods during cross-over, and separate adjustment means to effect fine axial adjustment of the die rods.

6. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, means to cause both rear and front carriages to cross over synchronously, anchor means slidably supporting the rear portions of the guide tubes from the carriages in the rear frame, means slidably supporting the forward portions of the guide tubes from the carriages of the forward frame, means on at least one said carriage in the forward frame to cause the guide tube supporting means to move out of the path of the other guide tube supporting means during a cross-over, fluid cylinders carried by the carriages of the rear frame, pistons in said cylinders coupled to the anchor means to retract the guide tubes and die rods during cross-over, a threaded section on each said cylinder, a toothed nut engaging said threaded section and axially confined in the carriage, a worm wheel engaging each said toothed nut, and motors to independently drive the said worm wheels to effect fine axial adjustment of the cylinders and thus the die rods.

7. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, chain means interconnecting the pair of carriages in the rear frame to give a cross-over movement, chain means interconnecting the pair of carriages in the forward frame to give a cross-over movement, a shaft rotationally coupling the two said chain means, a pair of hydraulic cylinders

coupled to the ends of a driving chain engaging a sprocket on the said shaft, valve means to control the flow of hydraulic fluid alternately to each cylinder to effect a cross-over movement of the said carriages, means supporting the rear portions of the guide tubes from the carriages in the rear frame, means supporting the forward portions of the guide tubes from the carriages of the forward frame, and means on at least one said carriage in the forward frame to cause the guide tube supporting means to move out of the path of the other guide tube supporting means during a cross-over.

8. Improved feed mechanism for draw benches comprising at least two guide tubes carrying die rods, frames near the forward and rear ends of the said guide tubes, a pair of carriages in the rear frame disposed in different horizontal planes, a pair of carriages in the forward frame also disposed in different horizontal planes, anchor means slidably supporting the rear portions of the guide tubes from the carriages in the rear frame, means slidably supporting the forward portions of the guide tubes from the carriages of the forward frame, means on at least one said carriage in the forward frame to cause the guide tube supporting means to move out of the path of the other guide tube supporting means during a cross-over, fluid cylinders carried by the carriages of the rear frame, pistons in said cylinders coupled to the anchor means to retract the guide tubes and die rods during cross-over, a threaded section on each said cylinder, a toothed nut engaging said threaded section and axially confined in the carriage, a worm wheel engaging each said toothed nut, means to rotate the worm wheels, chain means interconnecting the pair of carriages in the rear frame to give a cross-over movement, chain means interconnecting the pair of carriages in the forward frame to give a cross-over movement, a shaft rotationally coupling the two said chain means, hydraulic means to revolve the said shaft, a motor and pump to supply the hydraulic power, and valve means to control the direction of rotation of the said shaft by the said hydraulic means.

9. Improved feed mechanism for draw benches according to claim 8 characterised by switch means carried by the carriages coupled to allow actuation of the said motor only when the said guide tubes and die rods are retracted.
